[57] CLAIM

The ornamental design for a clock and timer attachment
for telephone, as shown and described.

DESCRIPTION

FIG. 1 is a top left front perspective view of a clock and
timer attachment for telephones showing my new de-
sign;

FIG. 2 is a front elevational view thereof;

FIG. 3 is a right side elevational view thereof;
The bottom and rear of the attachment are substan-
tially plain and unornamented.

FIG. 1

FIG. 2

FIG. 3
